W. Va., a corporation of West Virginia

Application April 29, 1948, Serial No. 146,036

Term of patent 14 years

(Cl. D36—2)

To all whom it may concern:

Be it known that I, Marvin G. Yutzey, a citizen of the United State of America, residing at Moundsville, in the county of Marshall and State of West Virginia, have invented a new, original, and ornamental Design for a Candy Jar, of which the following is a specification, reference being had to the accompanying drawing, forming a part thereof, wherein:

Fig. 1 is a side elevational view of a candy jar showing my new design;

Fig. 2 is a partial vertical sectional view;

Fig. 3, a top plan view; and,

Fig. 4, a horizontal sectional view, on the line 4—4 of Fig. 2.

I claim:

The ornamental design for a candy jar, as shown.

MARVIN G. YUTZEY.
